UNITED STATES PATENT OFFICE.

ALBERT McDOWELL, OF SELMA, CALIFORNIA, ASSIGNOR OF ONE-HALF TO
J. A. STROUD, OF SAME PLACE.

COOLER.

SPECIFICATION forming part of Letters Patent No. 424,125, dated March 25, 1890.

Application filed July 8, 1889. Serial No. 316,865. (No model.)

To all whom it may concern:

Be it known that I, ALBERT McDOWELL, of Selma, Fresno county, State of California, have invented an Improvement in Coolers; 5 and I hereby declare the following to be a full, clear, and exact description of the same.

My invention relates to that class of coolers in which the evaporation of the water is made to rapidly take place by exposing a considerable surface of saturated fabric, whereby the 10 temperature within the cooling-vessel is lowered.

My invention consists in a suitable vessel for the water, having within it a vessel for the 15 material which is to be kept cool, covers of fabric or other suitable absorbent material fitted to the outside of the water-vessel and having end flaps falling over the edges of said vessel into the water, rolls of absorbent material or fabric passed around the exterior of the vessel and having extension-flaps projecting 20 into the water, an outer belt or band fitted around the vessel outside of the rolls, whereby an air-space is formed between said belt or 25 band and the vessel, a suitable roof or top for the vessel and absorbent coverings therefor, and minor details of construction and arrangement, all of which I shall hereinafter 30 fully describe, together with the objects of my invention.

Referring to the accompanying drawings for a more complete explanation of my invention, Figure 1 is a vertical cross-section of my cooler. Fig. 2 is a horizontal section on line 35 $\alpha\alpha$, Fig. 1.

A is the outer vessel, made of any suitable material. B is the inner or receiving vessel for containing the materials to be kept cool. This inner vessel is enough smaller than the 40 outer one to leave a surrounding space a , and said inner vessel is held down in place by any suitable means—as, for instance, by the flanges a' and the pivoted or swinging arm a^2 . The outer surface of the vessel A is covered 45 with any suitable absorbent substance C, preferably fabric of some kind, said absorbent material having flaps c , which bend over the edge of the vessel and fit down into the space a between said vessel and the inner vessel.

50 D are rolls of absorbent material—such, for example, as coarse muslin or other fabric—

and which are passed around the outer vessel and in contact with the fabric cover C. These rolls have extension-flaps d , which hang down into the space a .

55

E is an outer belt or band of suitable fabric—such, for example, as duck or canvas—which is strapped and fastened around the exterior of the outer vessel A and presses against the rolls D. There is therefore formed 60 between the outer vessel and the belt or strap E an air-space F, which is made by the rolls holding the strap or band out.

G is the roof for the outer vessel, formed with swinging sides g , which are provided 65 with covers g' of a suitable absorbent material—such as bagging or other fabric—and these covers have extension-flaps g^2 , which hang down in the space a . The extension-flaps d of the rolls pass over the tops of the 70 swinging sides g and down into the space a within the vessel A, and thus the rolls are in contact with the fabric covers g' of said sides.

H is a fabric cover for the entire cooler, said cover being secured to the roof and hanging 75 down on each side of the cooler.

The operation of the cooler is as follows: Water is placed in the outer vessel A, and the inner vessel B is set down into the water, the level of which, however, is not high enough 80 to allow it to run over into the inner vessel. In this inner vessel is placed the material to be kept cool. The water fills the space a , and consequently the flaps c and d and g^2 lie in the water in space a . The fabric covering C 85 of the vessel A is first saturated with water, as are also the rolls D and the fabric cover g' of the roof, and the extension-flaps, passing down into the water, keep all these parts thoroughly saturated as long as there is any 90 water left. The evaporation from these saturated surfaces is great enough to reduce the temperature within the vessel B and serve the purpose intended.

The rolls D have not only the function 95 heretofore described of holding the encircling belt or band E out to form the air-space F, but are also for the purpose of keeping the covering C wet longer than it otherwise would remain wet. This they do by reason of not 100 parting with their moisture as quickly as the covering C, but hold it longer, and as they

come in contact with the covering they keep it wet, and they also keep the roof-covering wet.

The circulation of air through the space F 5 between the outer belt or band and vessel assists materially in the evaporation and in the general result.

In order to obtain access to the vessel, the hinged or swinging sides *g* of the roof are 10 turned backwardly, thereby opening the top, or if water alone is desired from the inner vessel this may be drawn off by a siphon or any other suitable means.

Having thus described my invention, what I 15 claim as new, and desire to secure by Letters Patent, is—

1. A cooler consisting of an outer vessel for containing water, an inner vessel for containing the material to be kept cool and sufficiently smaller than the outer vessel to leave 20 a water-space around it, and a covering of fabric or other absorbent material about the exterior of the outer vessel and having extension-flaps turning over its edges into the 25 water-space between the two vessels, substantially as described.

2. A cooler consisting of the outer vessel for containing water, the inner vessel for containing the material to be cooled and sufficiently smaller than the outer vessel to leave 30 a surrounding water-space, a covering for the outer vessel of fabric or other absorbent material, having extension-flaps passing over the edge of the outer vessel into the water-space, 35 and the rolls of fabric or other absorbent material passing around the outer vessel and in contact with its covering, said rolls having extension-flaps passing down into the water-space, substantially as described.

3. A cooler consisting of the outer vessel for containing water, an inner vessel for containing the material to be cooled and sufficiently smaller than the outer vessel to leave a surrounding water-space, a covering for the 40 outer vessel of fabric or other absorbent material, having flaps extending down into the water-space, rolls of fabric or other absorbent material passing around the outer vessel and in contact with its covering, said rolls having 45 flaps extending down into the water-space, and an outer belt or band covering the rolls 50

and outer vessel and forming a space for air between itself and the covering of said vessel, substantially as described.

4. In a cooler, the combination of the outer vessel for containing water, the inner vessel for containing the material to be cooled and sufficiently smaller to leave a water-space, a covering for said outer vessel of fabric or other absorbent material and having flaps extending down into the water-space, a roof for said outer vessel having swinging sides, and a covering of fabric or other absorbent material for said sides and having flaps passing down into the water-space, substantially as 65 described.

5. A cooler consisting of the outer vessel, the inner vessel, leaving a space between for the water, the absorbent or fabric covering C for the outer vessel having extension-flaps 70 passing down into the water-space, the roof for the outer vessel having swinging sides, the absorbent or fabric covering for said swinging sides, having extension-flaps passing down into the water-space, and the rolls of 75 fabric or other absorbent material passing around the outer vessel and roof and in contact with their coverings and having flaps extending down into the water-space, substantially as described.

6. A cooler consisting of the outer vessel, the inner vessel, leaving a water-space between them, the absorbent or fabric covering for the outer vessel, having flaps extending down into the water-space, the roof for the 85 outer vessel having the swinging sides, the absorbent or fabric covering for said sides, having flaps extending down into the water-space, the rolls of fabric or other absorbent material passing around the outer vessel and 90 the roof and in contact with their coverings and having flaps extending down into the water-space, and the outer belt or band around the outer vessel and rolls, forming the air-space F, substantially as described.

In witness whereof I have hereunto set my hand.

ALBERT McDOWELL.
